TOP FOR RUMBLE SEATS FOR
AUTOMOBILESBenton Settle Rinker and Mary W. F. Speers,
Washington, D. C.

Application April 2, 1936, Serial No. 72,398

3 Claims. (Cl. 296—99)

The invention relates to new and useful improvements in a top for rumble seats of automobiles.

An object of the invention is to provide a foldable top which may be detachably connected as a unit to the body of the vehicle without altering the construction of the body, and which, when folded, may be shifted into the pit containing the rumble seat for storage.

10 A further object of the invention is to provide a foldable top of the above type, which, when extended, may be connected firmly to the back of the seat and the body of the vehicle by a manipulation of the supporting frame of the top.

15 A still further object of the invention is to provide supporting guides for the frame of a foldable top of the above type which are detachably clamped to the body and extend into the pit beneath the deck of the body at the front of the 20 pit so that when said folded top is moved along the guides and stored within the pit, it will be placed out of the way of the passengers.

25 A still further object of the invention is to provide a supporting means for a foldable top of the above type which includes manually controlled devices for automatically raising the frame from the pit at the will of the passenger.

These and other objects will in part be obvious and will in part be hereinafter more fully disclosed.

In the drawings—

Figure 1 is a view partly in side elevation and partly in section, showing the improved foldable top and supporting means therefor, with the top 35 folded and stored in the pit in front of the rumble seat;

Fig. 2 is a view similar to Fig. 1, showing the foldable top and frame raised from the pit preparatory to unfolding and extending the same;

40 Fig. 3 is a view similar to Fig. 1, but showing the top partly unfolded in broken lines and fully extended in full lines preparatory to the connecting of the same to the body and the back of the seat by a manipulation of the frame;

45 Fig. 4 is a view similar to Fig. 3, but showing the top as connected to the back of the seat and the body of the vehicle;

Fig. 5 is a transverse sectional view through one of the clamping devices and showing a portion 50 of the supporting guide which is carried thereby and a portion of the frame of the top, and also the latch for securing the frame in a raised position;

55 Fig. 6 is a detail of the latch;
Fig. 7 is a view showing a slightly modified form

of the invention wherein means is provided for automatically raising the top from the pit when released by the operator;

Fig. 8 is a sectional view on the line 8—8 of Fig. 7;

Fig. 9 is a detail showing more or less diagrammatically the top applied to the vehicle and the side curtains in place, and

Fig. 10 is a sectional view through the top as applied, and showing the side curtain in full lines 10 at one side in place for use and in broken lines in folded position, and showing the side curtain at the other side in folded position within the top.

The invention has to do with a foldable top for rumble seats of automobiles. The foldable top 15 includes a main frame to which is attached a foldable top supporting frame extending from said main frame to the rear seat. There is also attached to this main frame a top supporting frame which extends from the main frame to the body 20 of the vehicle. A flexible top covering is attached to these top supporting frames and extends all the way from the forward side of the front frame to the rear side of the rear frame, thus making a complete top covering extending 25 all the way from the body of the vehicle to the back of the seat. The foldable top supporting frame is so constructed that the section of the top in rear of the main frame when detached from the seat may be folded against the main 30 frame. The frame for the top located in front of the main frame can also be folded against the main frame. Thus it is that the top is folded into a compact assembly at the opposite sides of the main frame. The main frame is mounted on 35 guides which are detachably connected to the body of the vehicle without, in any way, altering the construction of the vehicle. Each guide is rigidly secured to a clamping member which hooks over the inner edge of the trough at the 40 sides of the opening leading to the pit in front of the rumble seat. A clamping screw bearing against the under face of the trough serves as a means for detachably connecting the guide to the body. The main frame has projecting lugs 45 which are directed along the guide so that the folded top can be stored in the pit in front of the seat, and of the passenger sitting thereon. The guide is curved and extends well underneath the deck in front of the opening leading to the 50 pit, so that when the top is lowered it is stored underneath the deck and does not, in any way, interfere with the passenger room in front of the seat. The foldable top, together with the clamps and guides, form a unit which may be 55

readily attached to or detached from the body of the vehicle without altering the construction of the vehicle, and at the same time, the top may be folded and stored within the pit in front of 5 the rumble seat or raised and attached to the body and the seat for protecting the passengers. In one form of the invention, means is provided for automatically sliding the main frame along the guides to a raised position, which automatic 10 means is under the control of the passenger.

Referring more in detail to the drawings, the automobile to which the invention is applied is of the rumble seat type. It includes a body 1 having the usual rigid top portion 2, in rear of 15 which is a deck 3 having an opening 4 therethrough. This opening 4 leads to the pit 5 in which is located the rumble seat 6. Associated with this rumble seat 6 is a back 7 which, when folded, closes the opening 4 leading to the pit. 20 The deck 3 of the body is bent downwardly at 8, thence laterally at 9, and thence upwardly at 10, along the sides and at the front of the opening 4. This provides a housing adapted to receive a flange 11 formed along the sides and across the 25 top of the back 7 for the seat, so that when the seat is in closed position, this flange extends into this housing, and thus the opening is tightly closed. These parts are all of the usual construction and further detail description thereof 30 is not thought necessary.

The improvement resides in a foldable top of unit structure which may be removably attached to the body without altering the structure thereof. The foldable top includes a main frame 12 which is preferably one integral structure including side members and a top cross member 12a. Pivoted to this main frame at the outer end thereof is a front top frame member 13. Said member is pivoted at 14 to the main frame. This 40 frame member 13 is preferably of one piece and includes side members and a cross member 15. Also pivotally attached to the main frame 12 is a rear top frame 16. This rear top frame includes side members and a cross member 17. Each 45 side member is made in three sections which are pivoted together. The section 18 is pivoted to the main frame 12. The section 19 is pivoted to the section 18 at 20. There is a section 21 which is pivoted to the section 19 at 22, and these sections carry the cross member 17. This makes up a foldable rear top section which may be shifted to a position close to the main frame 12, as shown in Figures 1 and 2, or extended, as shown in Figures 3 and 4. When the sections of the rear frame 50 are in extended position, the ends of the section 19 contact with stop pins 23 and 24, respectively, and this limits the movement of the sections relative to each other, holding the same in substantial alinement.

60 There is a flexible covering 25 which is attached to the front top frame 13 and the rear top frame 16 in the usual manner. Said flexible covering or top extends over the cross member 15 and is riveted or otherwise secured thereto. Said flexible covering or top also extends beyond the member 17 and is riveted or otherwise secured thereto. The flexible covering or top has depending side portions 25a.

The main frame is supported by guiding members 26. There is a guiding member at each side of the pit, and this guiding member extends all the way from the opening to the floor of the pit. The guiding member is curved forwardly as indicated at 26a, and thence extends downwardly 70 as indicated at 26b. These guiding members are

close to the forward side of the pit and placed so as to be well out of the way of the passengers sitting on the seat 6. Each guide at the upper end thereof has an auxiliary guiding member 27 spaced from the guide 26. The side members 12 of the main frame are connected by a cross rod 28. This cross rod is placed a short distance from the lower ends of the side members of the frame and at the extreme lower end thereof are lugs 29. There is a lug on each side member. The 10 end of the rod 28 projects through the frame and forms a lug 30. The lugs 29 and 30 are adapted to contact with and move along the guide 26. These guides 26 are secured to the body by a clamping means. There is a clamp for each 15 guide. These clamps are similar in construction and a description of one will answer for the other. Each clamp includes a member 31 having a hook-shaped upper end 32 which is adapted to engage over the member 10 of the body. Said clamp has 20 a transversely extending member 33 in which is mounted a clamping screw 34. This clamping screw engages the member 9 of the body and draws the hook end 32 into firm contact with the body. Thus it is that each clamping member 25 may, at will, be attached to or detached from the body of the vehicle and without, in any way, altering the structure of the vehicle. The guide 26 is attached to its respective clamping member by rivets or bolts which are indicated diagrammatically at 35, 35.

Pivoted connected to the guide 26 is a latch 36. Said latch 36 is pivoted at 37 to the guide. The latch has a laterally projecting handpiece 38 whereby it may be easily manipulated. The latch 35 is also provided with a recess forming locking shoulders 39 and 40. When the top is in set raised position, this latch engages the lug 30 on the rod 28 and will hold the main frame located in a set position on the guides. 40

Attached to the cross member 15 is a flexible member 41 which extends all the way across the front frame. Pins 42 are attached to the upper portion of the body 2 and are so positioned that the flexible member 41 may be raised to contact 45 therewith when the top is extended, and when said flexible member is pressed against the pins, they will become embedded in the flexible member. This will make a firm locking joint between the front frame and the upper portion of the 50 body of the vehicle. The cross member 17 of the rear frame is provided with locking hooks 43 which are adapted to engage the flange 11 at the back of the seat for locking the rear frame to the back of the seat. 55

The top when folded against the main frame may be positioned within the pit in front of the passengers, and with the lugs 29 and 30 resting on the guide 26. The guide 26 is provided with bracket plates 44 which house the lugs 29 and 60 30, and thus the main frame is held in rigid position when it is moved into the pit for storage. Straps 45 attached to the guides 26 are utilized for holding the top in its folded position. The strap is attached at 46 to the guide 26 and is 65 adapted to be detachably connected by hooking or otherwise to the guide 26 at 47.

When it is desired to use the top, the strap is released, and the folded top, as a unit, is slid along the guides 26, thus bringing the top from 70 the pit to a position above the deck of the body of the vehicle, as shown in Fig. 2. The front section 13 is then moved to a raised position as indicated in full lines in Fig. 3. The rear top frame is moved to an extended position, as shown 75

in full lines in Fig. 3. The main frame is raised above its set position slightly, and the latch 36 may be connected to the lug 29 for holding it in this raised position while the top sections are being extended and placed for connection to the body and the back of the seat, respectively. The latch is then released, and the main frame moved downward to the position shown in Fig. 4. When in this extreme raised position shown in Fig. 3, 10 and the front frame member is placed in engagement with the pins, the sides of the front frame member and the sides of the rear frame member are raised slightly above alignment, as shown in this Figure 3. After the flexible member 41 is 15 placed against the pins and the member 17 brought into position for engagement with the flange 11 at the rear of the seat, then the main frame is lowered to the position shown in Figure 4. The straightening out or bringing into alignment of the front and rear frame members, 20 will force the flexible member on to the pins, and the hooks 43 on to the flange at the rear of the seat, and thus it is that the foldable top is rigidly clamped to the top of the vehicle and the back of 25 the rumble seat. The latch not only holds the main frame in this set position when it engages the lug 30, but the auxiliary guide 27 cooperating with the guide 26 and contacting with both lugs, will tend to hold said main frame member 30 in rigid set position. This makes a very strong and durable connection for the foldable top when extended to the top of the vehicle and the back of the seat. When it is desired to fold the top and store it in the pit, the latch is removed and 35 the main frame raised to the position shown in Figure 3, which will release the hooks 43 and also the flexible member from engagement with the pins. The front frame 13 is then lowered to folded position, and the rear frame member is 40 folded as indicated in Fig. 3, so as to bring the top frame members and the flexible top into a compact position adjacent the main frame 12. The latch 36 is then released so that the folded top, as a unit, is moved along the guides which 45 will direct the unit folded top forwardly beneath the deck 3 and store the same well out of the way of the passengers. When the top is fully lowered, it will be held in position on the guide by a bracket 26c, and the straps may be attached 50 for preventing the top from unfolding.

From the above it will be apparent that we have provided a unit foldable top for the rumble seat of an automobile which may be attached to a vehicle body without altering the structure 55 thereof, and when it is attached, it may be readily folded and moved into the pit for storage, or the top may be removed from the pit and extended and connected to the body and the seat so as to serve as a covering for the passengers.

In Figures 9 and 10 of the drawings, there are 60 shown side curtains which may be used in connection with the foldable top. The side curtain 48 extends about the side members of the front and rear top frames and is secured thereto in the usual way. Said top is provided with hooks 49 at spaced intervals which may be clamped beneath the body member 9, and thus the side curtain secured to the body as well as the frame. The side curtain is adapted to be folded against 65 the under side of the top as shown in Fig. 10, and when in folded position, it is held by straps 50 engaging the hooks 49. In this Fig. 10, the side curtain 51 is shown as folded against the top and secured by the strap 53. There is also 70 shown in broken lines, the folding curtain 48

and the securing of the same by engaging the hook 49 thereof with the hook 52 attached to the curtain.

In Figures 7 and 8, there is shown a modified form of construction wherein the foldable frame 5 supporting the flexible covering or top is automatically raised from the pit and automatically distended. In this form of the invention, the main frame 12 is of the same construction as described in connection with Figures 1 to 4. The 10 front frame 13 is also of the same construction. The front frame is pivoted at 12a to the main frame. The rear frame supporting the flexible covering or top includes a section 18, a section 19 and a section 21 which is similar to that described above. Connected to the sections 18 and 19 are links 53 and 54. These links are pivoted together at 55. A rod 56 is connected to the pivot 55 at its upper end, and is pivoted at 57 to a lever 58 which in turn is pivoted at 59 to the 20 main frame 12. The section 21 has an extension 21a. The link 60 is pivoted to this extension at 61 and is also pivoted to the section 18 at 62. There is a link 63 which is pivoted to the end of the section 19, which is adjacent the main frame 25 12, and this link 63 is likewise secured to the pivot 55. It is understood that there are similar links and levers on both sides of the main frame. The flexible covering is attached to the top frames in the manner described, but has been omitted 30 from Fig. 7 for the sake of clearness.

The main frame is provided with a cross rod 28a which extends through the frame and provides lugs 29. The frame is also provided with a rod 28 which extends through the frame to 35 provide lugs 30 such as described above. There is a guide 64 at each side of the pit for the lugs 29 and 30 carried by the main frame 12. Each guide is in the form of a tube, and the lugs extend through a slot 65 into the tube. The tube 40 at its upper end is clamped to the body in the manner shown in Fig. 5, and at its lower end, it is connected to a bracket 66 which rests on the floor. Located within this tube is a compression spring 67. There is a latch 68 pivoted at 45 69 to the guide 64 and spring-pressed to the position shown in Fig. 7. There is also a latch 70 pivoted at 71 to the guide 64. When the top frame sections are folded against the main frame, and the main frame with the folded top 50 lowered into the pit, the lug 29 will compress the spring 67 and the latch 68 will engage the rod 28a and hold the frame in its stored position. Upon releasing the latch 68 the spring will force the lug 29 along the guide 64 and this will raise 55 the frame from the opening leading to the pit, and as the frame reaches the position shown in Fig. 7, the lever 58 which normally extends at right angles to the main frame 12 will contact with the body, and will be turned in a clockwise 60 direction, and this, through the rod 56 and the links 53 and 54, will cause the front top frame 13 to move to a raised position bringing the elastic member 41 opposite the pins 42 on the top of the vehicle. This will also cause the section 65 18 to swing to the raised position shown in Fig. 3. The link 63 will swing the section 19 into alignment with the section 18 and the link 60 will operate to swing the section 21 into alignment with the section 19. This extends the rear 70 sections of the top frame and brings the hook 43 into a position adjacent the flange on the back associated with the rumble seat. Thus it is that when the passenger releases the latch 68, the folded frame carrying the flexible covering or 75

top will be moved automatically from its stored position within the pit to a raised position, and the top frame members extended ready for the clamping of the same against the top of the vehicle and the back of the seat. The passenger then pulls down upon the frame 12 so as to bring the cross bar 28a into position for engagement with the latches 70 and this will draw down on the sections 13 and 18 of the top frame, bringing them into alignment as described in connection with Figures 3 and 4, and also causing a connection between the flexible member 41 and the pins 42, and likewise the hook 43 and the flange 11 at the back of the seat. All the passenger has to do is to release the latches, and then the top will move to its extended position, and by drawing down on the frame, it will be connected to the vertical top and the back of the seat. When it is desired to fold the top, then the latch 70 is released, the frame 12 is raised so as to release the flexible member from the pins and the hook 43 from the back, after which the top frame members can be folded against the main frame member and the main frame member moved along the guides compressing the spring until the rod 28 passes the latches 68, when they will automatically engage the latch and hold the folded top in its stored position.

30. While the invention has been described in detail as applied to the rumble seat of an automobile, it is to be understood that this foldable top and the means for supporting the same may be used in connection with boats, launches 35 and any other type of moving vehicle where there is a pit having a seat for a passenger.

It is obvious that many changes may be made in the details of construction and the arrangement of the parts without departing from the spirit of the invention as set forth in the appended claims.

Having thus described the invention, what we claim as new and desire to secure by Letters Patent, is

45. 1. A foldable top for the seat of a vehicle comprising supporting bracket members secured to the body at the sides of the seat opening, a guide carried by each of said bracket members and extending into the pit of the seat opening, a supporting frame including a pair of side members 50 slidable on said guides whereby to permit the said supporting frame to be raised and lowered, a front frame section carried by said supporting frame and adapted, in folded position, to lie against the said supporting frame, a rear frame section carried by said supporting frame and adapted, in folded position, to lie against said supporting frame, a flexible cover for the front and rear frame sections, vertically spaced holding 55 means at the lower ends of said side members, and means on said guides engageable with said spaced holding means to hold said supporting frame in different set positions, said holding means being disposed so that, when the side members 60 of said supporting frame are in one set position, the said supporting frame will be elevated so as to permit the front and rear frame sec-

tions to be extended to a position for engagement with the vehicle, the connection between said supporting frame and the front and rear frame sections being at one side of the normal locked position when in this set position with the front and rear frame sections out of alignment whereby a movement of the side members of said supporting frame to a second set position will force said front and rear frame sections toward alignment and cause the same to tightly engage the body of the vehicle.

2. A foldable top for the seat of a vehicle comprising supporting bracket members secured to the body at the sides of the seat openings, a guide carried by each of said bracket members and extending into the pit of the seat opening, a supporting frame including a pair of side members slidable on said guides whereby to permit the said supporting frame to be raised and lowered, a front frame section carried by said supporting frame and adapted, in folded position, to lie against the said supporting frame, a rear frame section carried by said supporting frame and adapted, in folded position, to lie against said supporting frame, a flexible cover for the front and rear frame sections, spring means associated with each of said guides and connected to said side members for normally raising said supporting frame whereby the front and rear frame sections may be extended, means on said guides for engaging the side members of said supporting frame to hold the said supporting frame at a set position to maintain the front and rear frame sections in their extended positions in engagement with the vehicle, and latch means at the lower ends of said guides for engaging the side members of said supporting frame and holding the folded top in stored position.

3. A foldable top for the seat of a vehicle comprising supporting bracket members secured to the body at the sides of the seat opening, a guide carried by each of said bracket members and extending into the pit of the seat opening, a supporting frame including a pair of side members slidable on said guides whereby to permit the said supporting frame to be raised and lowered, a front frame section carried by said supporting frame and adapted, in folded position, to lie against the said supporting frame, a rear frame section carried by said supporting frame and adapted, in folded position, to lie against said supporting frame, a flexible cover for the front and rear frame sections, spring means associated with each of said guides and connected to said side members for normally raising said supporting frame, means including a lever mechanism operable upon the raising of said supporting frame for automatically extending said front and rear frame sections, and means on said guides for engaging the side members of said supporting frame to hold the said supporting frame at an elevated set position to maintain the front and rear frame sections in their extended positions in engagement with the vehicle.

BENTON SETTLE RINKER. 65
MARY W. F. SPEERS.
